UNITED STATES PATENT OFFICE.

MICHAEL C. REGAN, OF THE UNITED STATES ARMY.

LAMP ATTACHMENT FOR CELLS.

1,210,365.

Specification of Letters Patent.

Patented Dec. 26, 1916.

Application filed January 7, 1916. Serial No. 70,791.

To all whom it may concern:

Be it known that I, MICHAEL C. REGAN, of the United States Army, a citizen of the United States, stationed at Fort Mott, in the county of Salem and State of New Jersey, have invented certain new and useful Improvements in Lamp Attachments for Cells; and I do hereby declare the following to be a full, clear, and exact description of the invention, such as will enable others skilled in the art to which it appertains to make and use the same.

The present invention relates to improvements in lamp attachments for cells, and has for an object to provide an improved attachment whereby miniature or other electric lamps may be attached to dry or other cells and supported thereon to swing into and out of engagement with one terminal or connector for lighting or disconnecting the lamp.

Another object of the present invention resides in providing an improved attachment of the above character which will be simple in construction and economical in manufacture, and will be designed for ready attachment to any of the approved types of cells now in use.

With these and other objects in view the invention consists in the novel details of construction and combinations of parts more fully hereinafter disclosed and particularly pointed out in the claims.

In the accompanying drawings forming a part of this application, and in which similar reference symbols indicate corresponding parts in the several views: Figure 1 is an elevational view of a portion of a battery illustrated with the improved attachment as connected thereto. Fig. 2 is a top plan view of the same. Fig. 3 is a perspective view of one member of the improved attachment. Fig. 4 is a perspective view of the supplemental member. Fig. 5 is an elevational view of a portion of a battery illustrated as equipped with a twin lamp holder constructed in accordance with the present invention; and Fig. 6 is a top plan view of the same.

Referring more particularly to the drawings, and in detail to Figs. 1 to 4 inclusive, 1 designates a dry or other cell having a central positive terminal 2 and a zinc negative terminal 3 at one edge thereof. From the terminal 2 extends a binding post 4, threaded, in the usual manner, to receive a binding nut 5. Similarly, a binding post 6

is connected to the negative terminal 3, the same being threaded to receive the binding nut 7.

A miniature, or other electric lamp is shown in Figs. 1 and 2 as being of the usual construction comprising a bulb 8, a threaded base 9 constituting one terminal, and a head 10 insulated and projecting from the base 9 and forming the second terminal.

The head 10 on the base 9 is adapted to occupy a socket in the upper end of the binding post 4 when the lamp is in the position shown in Figs. 1 and 2, where it is supported by the improved lamp holder and connected to the opposite terminal 3 so as to place the same in circuit with the battery 1, thereby lighting the lamp.

The base 9 of the electric lamp is adapted to thread or be otherwise received into a lamp socket 11, which is formed as disclosed to advantage in Figs. 1 and 4, by a coaxial series of convolutions bent from one end of a single wire strand. From the upper end of the socket or convolutions 11, the wire strand 12 is carried horizontally to provide an arm 12; and at the opposite end of the arm 12 the wire is wound to provide one or more coils 13, imparting resiliency to the lamp holder, and from the coils 13 the opposite end of the wire strand is bent vertically, forming a trunnion 14.

The vertical trunnion 14 is fitted to swing in a bearing 15, furnished by a series of coaxial convolutions bent centrally from a second wire strand, the lower end of which is carried horizontally to supply an arm 16 having its terminal end flattened and bent circularly, as shown clearly at 17 in Fig. 3, to embrace the binding post 6, whereon it is secured by the nut 7. From the upper end of the convolutions 15 the wire strand is carried horizontally to provide an arm 18, and vertically to provide a holder 19 to which may be secured a reflector. This reflector holder may be dispensed with if desired.

After the attachment is secured to the cell 1, it will be seen that the lamp, which is carried in the socket 11 supported from the arm 12, may swing freely in a horizontal plane on the trunnion 14 about the bearing 15 as a center. When swung to the position shown in Figs. 1 and 2, the terminal head 10 will engage the socket in the binding post 4, and this engagement will be yieldingly preserved by the action of the resilient coils 13. By slight pressure on the lamp or arm

12, however, the coils 13 will yield and permit the head 10 to disengage the socket and allow the lamp to be swung out of electrical connection with the terminal 2, thus extinguishing the same. The lamp and holder will also readily yield when encountering any obstruction, so as to prevent possible breakage of the lamp.

Referring now more particularly to Figs. 10 5, 6 and 7, the battery, terminals, binding posts and nuts, are similar to those shown in Figs. 1 and 2, and are similarly numbered, it being understood that either form of the device may be attached to the same character of cell.

Over the central binding post 4 is secured, by a nut 5, a flat spring 20 bent upwardly, as indicated at 21 and 22, to provide elevated and yielding ends 23 and 24 having sockets 20 25 and 26 pressed therefrom, and being further bent downwardly at their terminals to provide guides 27 and 28.

The threaded bases 9 of the lamps are received in the sockets 11, wound from a series 25 of convolutions, as described of the lamp holder in connection with the first form of the invention. The sockets 11 are carried on arms 12 formed with coils 13 and trunnions 14, as described and shown in Fig. 4.

30 To the opposite terminal 3 is attached a connector, shown more particularly in Fig. 7 to be formed from a single length of wire, or metal of any other equivalent form, bent centrally to provide a yoke 29, which is flattened, as indicated, to receive the pressure of the nut 7 and form good electrical connection. To either side of the yoke 29 the wire is bent into arms 30 and 31, and from the outer ends of the arms are bent 35 series of convolutions 32 and 33 forming bearings for receiving the trunnions 14 of the lamp holders.

The lamp holders are journaled to swing in the bearings 32 and 33 in a horizontal 45 plane, and into and out of engagement with the flat spring 20. When moved into engagement with the flat spring 20, the terminal heads 10 of the lamp bases 9 will first encounter the bent-over terminals 27 and 28 50 of the ends 23 and 24, and will depress such resilient ends to permit the holder and lamp to be swung farther to engage the heads 10 with the sockets 25 and 26, where the lamps and holders will be yieldingly held in connected position. The lamps are further held in yielding engagement by the coils 13 of the holders, and it will be appreciated that should the lamps strike against any object 55 both the coils 13 and the flat spring 20 will yield and permit the lamp to swing, thereby preventing damage thereto.

It is to be understood that while I have shown and described the members of this improved attachment as being constructed of 65 wire strands, nevertheless the same may be

of flat metal in one or more pieces, or of other suitable material. It will be further understood that the members of the attachment may be reversed, the lamp being connected to swing into and out of engagement with the outer terminal 6, and the reflector holding member, or either of the members shown in Figs. 3 and 7, connected to the central terminal 2. The device is also adapted for connection to other types of cells having differently arranged terminals than that shown in the drawing, and I do not desire to restrict myself to the forms of the invention shown in the drawings, as obviously changes may be made in the same without departing from the spirit of the invention, provided such changes fall within the scope of the appended claims.

I claim:

1. The combination with a cell having 85 projecting terminals, of a connector secured in electrical connection with one of said terminals and comprising a single length of wire bent centrally into a series of convolutions to provide a bearing, a lamp holder 90 formed from a single length of wire separate from said connector and including a journal fitted to swing in said bearings, a series of convolutions arranged to provide a lamp socket, coils bent from said wire 95 holder intermediate the journal and lamp socket, and a lamp removably fitted in said socket and having a projecting terminal adapted to electrically contact with the other terminal of the cell, substantially as 100 described.

2. The combination with a cell having 105 projecting terminals, of a connector bent from a single length of wire having one end coiled about one of the cell terminals, a series of convolutions bent intermediately of said wire connector to provide a bearing, an arm bent from the opposite end of said connector and extending from said bearing, a reflector holder carried on said arm and bent from the extremity of said wire connector, a lamp holder formed of a single 110 length of wire having one end arranged to provide a journal fitted to swing in said bearing, a series of convolutions bent from the opposite free end of said wire holder and constituting a lamp socket, a coil bent from said wire holder between said journal and lamp socket, and a lamp fitted in said 115 socket and having a projecting terminal adapted to electrically contact with the other cell terminal, substantially as described.

3. The combination with a cell having 125 projecting terminals, of a connector consisting of a single length of wire bent to encircle one cell terminal, a series of convolutions bent from said wire connector to provide a vertically disposed bearing, a lamp holder consisting of a single length of 130

wire bent at one end to provide a journal fitted to swing horizontally in said bearing, a series of coils bent from the opposite end of said wire holder to provide a lamp socket, 5 coils bent from said wire holder intermediate said journal and socket to impart resiliency thereto, a lamp fitted in said socket and having a projecting headed terminal, and a resilient arm disposed in electrical contact with the other cell terminal and having a depression 10 in its free end arranged to be occupied by the headed terminal of said lamp, substantially as described.

4. The combination with a dry cell having terminals projecting from the upper end thereof, a connector formed of a single length of wire bent to engage one of said cell terminals, series of convolutions bent 15 from said wire connector and providing

vertically disposed bearings, lamp holders 20 comprising each a single length of wire bent at one end to form journals fitted to swing horizontally in said bearings, series of convolutions wound from the opposite ends of said wire holders, coils bent from 25 said wire holders intermediate said journals and sockets, lamps fitted in said sockets and having projecting headed terminals, and a resilient arm in connection with the other cell terminal and having depressions for receiving the headed terminals on said lamps to removably and yieldingly secure the lamps in circuit with the cell, substantially 30 as described.

In testimony whereof, I affix my signature.

MICHAEL C. REGAN.
